(57) **CLAIM**

The ornamental design for a meniscus refixation system, as shown and described.

DESCRIPTION

FIG. 1 is a front perspective view of a meniscus refixation system according to the present invention, shown with a removable tissue protection sleeve.

FIG. 2 is a front view of the meniscus refixation system of FIG. 1.

FIG. 3 is a rear view of the meniscus refixation system of FIG. 1.

FIG. 4 is a left side view of the meniscus refixation system of FIG. 1.

FIG. 5 is a right side view of the meniscus refixation system of FIG. 1.

FIG. 6 is a top view of the meniscus refixation system of FIG. 1.

FIG. 7 is a bottom view of the meniscus refixation system of FIG. 1.

FIG. 8 is a front perspective view of a meniscus refixation system according to FIG. 1, shown without the removable tissue protection sleeve.

FIG. 9 is a front view of the meniscus refixation system of FIG. 8.

FIG. 10 is a rear view of the meniscus refixation system of FIG. 8.

FIG. 11 is a left side view of the meniscus refixation system of FIG. 8.

FIG. 12 is a right side view of the meniscus refixation system of FIG. 8.

FIG. 13 is a top view of the meniscus refixation system of FIG. 8; and,

FIG. 14 is a bottom view of the meniscus refixation system of FIG. 8.

The dashed lines illustrate environment that does not form a part of the present invention, and no claim is made to the material illustrated with dashed lines.
